UNITED STATES PATENT OFFICE.

JOSEPH TAYLOR, OF SACO, MAINE.

AUTO NUMBER PLATE.

Application filed June 18, 1925. Serial No. 38,003.

To all whom it may concern:

Be it known that I, JOSEPH TAYLOR, a citizen of the United States, residing at Saco, in the county of York and State of

5 Maine, have invented a new and useful Auto Number Plate, of which the following is a specification.

This invention has reference to license plates for motor vehicles, the primary object of the invention being to provide a plate supplied with a compartment for the reception of an identification card or the like, so that should the plate be lost, the owner of the plate may be readily determined by examining the identification card in the compartment.

Another important object of the invention is to provide an extension as forming a part of the plate which may be bent upwardly and held in spaced relation with the rear surface of the plate to provide a compartment.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

35 Figure 1 is a front elevational view of a license plate constructed in accordance with the invention.

Figure 2 is a rear elevational view prior to the bending upwardly of the extension.

40 Figure 3 is a sectional view taken on line 3—3 of Figure 1.

Figure 4 is a sectional view taken on line 4—4 of Figure 1.

Referring to the drawing in detail, the 45 reference character 5 indicates the body portion of the plate which is formed with

an extension 6 formed integral with the lower edge thereof, and disposed at a point substantially intermediate the ends of the body portion.

50 Slits 7 and 8 respectively extend from the outer edges of the extension 6 and provide lateral sections 9 adapted to be folded to overlie portions of the extension 6 in a manner as shown by Figure 4 of the drawing 55 to define a pocket or recess for the reception of an identification card or paper.

When the lateral sections 9 have been folded inwardly, the extension 6 may be folded upwardly to a position as shown by Figure 3 of the drawing. Tongues 10 are formed on the free end of the extension 6 and are designed to be folded into engagement with the body portion as shown by Figure 1 to hold the extension 6 in position 60 to support the identification plate which in the present showing is indicated by the reference character 11.

65 From the foregoing it will be obvious that due to this construction, the plate is supplied with a compartment or pocket for the reception of an identification card bearing the name and address to whom the plate was issued, so that should the plate be lost from the motor vehicle, a person may, by 70 examining the identification card readily ascertain the owner and return the plate.

I claim:—

A license plate including a body portion, 75 an extension formed integral with the lower edge of the body portion, lateral sections forming a part of the extension and adapted to be folded to overlie the extension to provide a pocket, said extension adapted to be folded to a position adjacent to the body portion, and means for holding the extension in its active position.

In testimony that I claim the foregoing as my own, I have hereto affixed my signature.

JOSEPH TAYLOR.
